UNITED STATES PATENT OFFICE

2,473,182

ADJUSTABLE FLUE OR CHIMNEY DAMPER
FOR FIREPLACES, FURNACES, AND THE
LIKE

Ernest A. Stretz, Compton, Calif.

Application October 6, 1944, Serial No. 557,536

1 Claim. (Cl. 126—288)

1

This invention relates to a damper, and more particularly to such a damper adapted to be utilized in flues or chimneys, or the like.

A primary object of this invention is the provision of an improved damper adapted to be positioned in the flue or chimney of a fireplace, furnace, or the like, characterized by means whereby the same may be adjusted to fit any desired size of flue or chimney.

An additional important object of this invention is the provision of such a damper which may be readily applied to existing chimneys or flues.

Still another object is the provision of such a damper having improved control means thereon adapted to extend exteriorly of the flue or chimney, whereby the position of the damper may be readily controlled.

Additional objects reside in the combinations of elements, arrangements of parts, and features of construction, all as will be more fully pointed out hereinafter, and disclosed in the accompanying drawings, wherein there is shown a preferred embodiment of this inventive concept.

In the drawings:

Figure 1 is a top plan view of one form of damper embodying features of this invention.

Figure 2 is a bottom plan view of the device shown in Figure 1.

Figure 3 is an end elevation view of the device shown in Figures 1 and 2.

Figure 4 is a side elevational view of the device.

Figure 5 is an enlarged fragmentary view of a constructional detail, and

Figure 6 is an enlarged fragmentary perspective view of an additional constructional detail.

Like reference numerals refer to like parts throughout the several views of the drawings.

Having reference now to the drawings, the damper is comprised of two members, one generally indicated at 10 comprising a fixed portion, and the other generally indicated at 11 comprising a movable portion. Referring, first, to portion 10, it will be seen that the same is comprised of two plates 12 and 13, the edges of each being rolled, as at 14 and 15, the rolled edge 14 being adapted to fit slidably within the roll 15. The plates 12 and 13 are bent at right angles, as at 16 and 17, respectively, to form a right angled flange, extending upwardly with respect to the plate portions. Adjacent the extremities of the portion 10, lugs 18 and 19 are struck from the material of the plates 12 and 13, respectively, and provided with apertures 20 therein (see Fig. 5) adapted to engage the extremities 20' and 21,

2

respectively, of roll portions 22 and 23, similar to roll portions 14 and 15, formed on one edge of damper member 11, which, it is noted, is comprised of two plate-like members 24 and 25. Similar rolls 26 and 27 are formed on the opposite edges of the plate-like members 24 and 25, the rolls 23 and 27 adapted to be slidably positioned within rolls 22 and 26, whereby the plates may be slidably moved with respect to each other.

10 Spaced lugs 30 are adapted to be struck from an intermediate portion of plate 12 and depend downwardly therefrom, and additional spaced lugs 31 are adapted to be struck from an intermediate portion of the plate 24, and similarly 15 depend therefrom. A lever 32 is adapted to extend between lugs 30, being pivotally secured thereto, as by a bolt 33 and nut 34, and is secured at one extremity to a link 35, as by a nut 36 and bolt 37. The opposite end of link 35 is secured, as by a nut 38 and bolt 39, between lugs 31 of plate 24.

From the foregoing the method of use and operation of the device should be readily understandable. The damper is first adjusted to the size of the flue in which it is desired to be utilized, by moving the plates 25 and 13 inwardly or outwardly with respect to their associated plates 12 and 24, respectively, the roll members 15, 23 and 27 being respectively slidable within the corresponding members 14, 22 and 26, and the device is then positioned within the chimney, plate member 10 being fixedly secured in any desired position in any desired manner therein. The extremity of the lever 32 extends outwardly from the flue or downwardly with respect thereto, in order to be readily accessible, and, it will be seen that movement of the lever 32 varies the position of plate member 11, which serves as a damper member within the flue.

40 From the foregoing it will be seen that there is herein provided a device accomplishing all the objects of this invention and others, including many advantages of great practical utility and commercial importance.

45 As many embodiments may be made of this inventive concept, and as many modifications may be made in the embodiment hereinbefore shown and described, it is to be understood that all matter herein is to be interpreted merely as illustrative and not in a limiting sense.

I claim:

In a damper assembly, the combination of two elongated base members of L-shape in cross section longitudinally and slidably secured in nested contact with each other with the outer surfaces

of the legs of one member in face to face contact with the inner surfaces of the corresponding legs of the other member, whereby the two members are capable of longitudinal sliding movement relative to each other for fitting the damper in a flue, a pair of flat members extending longitudinally of said base members, the same being in face to face contact and movable with respect to each other longitudinally of the base members, such movement corresponding to the relative movement of the base members with respect to each other, one edge of said flat members being disposed adjacent the outer flat side of one of the legs of said L-shaped base members and the legs of said L-shaped base members and pivotally mounted upon said flat side of said base members on an axis extending longitudinally thereof, a pair of lugs struck from one of said base members and a corresponding pair of lugs struck from one of said flat members, the lugs of each pair being in alignment with each other and with those of the other pair, a damper operating lever pivotally connected intermediate its ends between the lugs on said one of said base members, and a connecting link pivotally connected at one end between the lugs on said one of

said flat members and pivotally connected at its opposite end to the adjacent end of said damper operating lever.

ERNEST A. STRETZ.
